(57) **CLAIM**

The ornamental design for a multi-compartment trash can, as shown and described.

DESCRIPTION

FIG. 1 is a front elevation view of a multi-compartment trash can showing my new design in an open position;

FIG. 2 is a rear elevation view thereof;

FIG. 3 is a right elevation view thereof, the opposite side being a mirror image of the shown;

FIG. 4 is a top plan view thereof;

FIG. 5 is a bottom plan view thereof; and

FIG. 6 is an isometric view thereof illustrated with a first compartment shown in a lifted position therein; and,

FIG. 7 is an isometric view thereof illustrated with the first compartment and a second compartment shown in a lifted position therein.

1 Claim, 6 Drawing Sheets
